LOUIS STEINBERGER, OF BROOKLYN, NEW YORK.

TELEPHONE-RECEIVER CASING.

1,212,705.

Specification of Letters Patent. Patented Jan. 16, 1917.

Application filed January 13, 1913. Serial No. 741,862.

To all whom it may concern:

Be it known that I, LOUIS STEINBERGER, residing at Brooklyn, in the county of Kings and State of New York, have invented certain new and useful Improvements in Telephone-Receiver Casings, of which the following is a specification.

This invention relates to a telephone receiver casing, and the particular object of 10 the invention is to provide a casing of the usual form, comprising a body part for retaining the receiver mechanism, and a cover detachable therefrom adapted to comprise therewith a clamp for retaining the diaphragm in operative position, the cover serving 15 as the ear piece, and to provide a reinforcing section upon the body whereby to strengthen the larger end thereof, and to provide a substantial means for coöperating 20 to connect the cover to the body, and to arrange the reinforcing means so that it may serve as a substantial attaching member for the operative parts of the receiver mechanism.

25 A further object is to provide a metal ring having threads on its outer periphery and having parts adapted to be molded, or otherwise rigidly connected, as a relatively integral part of the body structure, the threads 30 on the ring being adapted to mate corresponding threads on the cover.

A further object is to provide a reinforcing member for the body part of a telephone receiver casing, said member comprising a 35 cup-shaped part adapted to fit within and be substantially rigidly connected with the inner surface of the flaring end portion of the body, and having localities properly prepared and arranged to serve as a substantial 40 means for connecting thereto the operative parts of the receiver mechanism.

A further object is to provide the cover with a reinforcing member rigidly attached thereto in a simple manner and having parts 45 arranged to coöperate with parts of the reinforcing member of the body whereby the cover may be readily attached to and removed from the body.

Other objects and aims of the invention, 50 more or less specific than those referred to

above, will be in part obvious and in part pointed out in the course of the following description of the elements, combinations, arrangements of parts and applications of principles, constituting the invention; and 55 the scope of protection contemplated will be indicated in the appended claims.

In the accompanying drawings which are to be taken as a part of this specification, and in which I have shown a merely preferred form of embodiment of the invention, Figure 1 is a transverse, central, sectional view through a receiver casing constructed and reinforced in accordance with this invention, the cover being detached, and a 60 diaphragm being illustrated in position to be clamped upon the body; Fig. 2 is a top plan view of the body portion of the casing; and Fig. 3 is a transverse sectional view 65 taken substantially on the plane of line 3—3 70 of Fig. 1.

Referring to the drawings for a more detailed description of the structure, the numeral 1 indicates the body portion thereof which is formed, or shaped, in the usual 75 manner with an aperture as 2 at one end, for the passage of wires, and which has its other end flared outwardly as at 3 to provide an enlarged annular portion for receiving the diaphragm 22.

80 Resting upon the upper annular surface of the flaring end 3 is a reinforcing ring 4, having threads 5 upon its periphery, said threads occupying a position relatively to the end surface of the casing similar to the 85 position ordinarily occupied by such threads as are usually provided for the attachment of the cover, as 12.

The ring 4 is formed as an integral part 90 of a cup-shaped member 6 having conically shaped walls depending within the hollow of the casing, and having sections cut away as at 7 for receiving portions of the material of the body. The cut away sections 7 may be of any shape or size but are preferably 95 circular and are also preferably flared inwardly so that the material of the body projecting into them may be held in dovetailed relation, as clearly shown in the drawings.

The lower wall 8 of the cup-shaped portion 6 is cut away for the greater part of its area to correspond to the inner diameter of the casing, a narrow ridge or flange as 9 however, being retained and being formed with threaded apertures 10. The apertures 10 are preferably arranged at uniformly spaced points around the flange 9 and are adapted to receive screws or other attaching means 10 for the operative mechanism of the receiver.

In constructing a receiver body in accordance with the provisions of this invention, the reinforcing member is inserted in position in a suitable mold and the material 15 of the body is poured into the mold so that portions thereof will enter the parts 7 and fill the same, and so that the outer surface of the cup-shaped portion 6, and the under surface of the ring 4 will be intimately engaged by the material of the body.

The reinforcing member may comprise any suitable material but is preferably formed of brass and it may of course be attached in other ways than that shown without departing from this invention. The receiver body portion is preferably of electrose 25 though obviously it may be formed of any other suitable material.

A receiver casing body constructed in the manner above set forth and clearly shown in the drawings is very substantial and the manner of forming the same is simple and inexpensive. The threads upon the metallic ring 4 are of course more substantial and 30 less susceptible to injury than threads formed upon the fickle material of the body as has been customary heretofore. The ring is disposed in a position to receive, and is capable of withstanding without injury, 35 the most severe shocks which may be inflicted upon the structure incident to careless handling thereof.

The cover 12 is preferably formed of the same material as the body and is formed 45 with the usual sound aperture 13 and marginal flange 14. The reinforcing member for the cover comprises a metallic ring 15 threaded upon its inner surface to mate the threads 5 of the body, and formed with a 50 plurality of apertures 16 into which the material of the flange 14 extends for rigidly connecting the ring to the making it in effect, a part of the flange.

As clearly shown in the drawing, the 55 threaded apertures 10 overlie depressions formed in the material of the casing and these depressions are threaded in continuation of the threads of the apertures so that together they form screw receiving sockets 60 for the attachment of the receiver mechanism. This construction has a peculiar advantage in that while the metallic flange serves particularly to withstand any strain applied to the screws, the relatively soft

material of the receiver casing serves in a 65 friction capacity to retain the screw against possible accidental rotation. The two parts thus comprise an efficient means for enabling the screws to serve their intended purpose. Furthermore, it will be noted that the 70 intermediate portion of the reinforcing ring lies in close contact with the material of the casing throughout its extent. This portion is held in rigid contact with the material 75 of the casing and is retained against any possible vibration independent of the casing by the attaching means illustrated.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense. It is also to be understood that the language used in the following claims is intended to cover all of the generic and specific features of the invention herein described and all statements of the scope 80 of the invention, which as a matter of language, might be said to fall therebetween.

Having thus described my invention, what I claim as new and desire to secure by Letters Patent, is:—

1. A telephone receiver casing, comprising a hollow cylindrical member open at one end, said cylindrical member being formed with a shoulder interiorly thereof adjacent said open end, a separately formed reinforcing ring arranged within said open end, said reinforcing ring having a flange-like part at its outer end for engaging the receiver cover and having a flange-like part at its inner end for engaging said shoulder, the intermediate portion of said reinforcing ring lying in close contact with the adjacent surface portion of the receiver casing throughout its extent, and there being openings formed through said adjacent portion into which portions of the material of the receiver casing are molded so as to comprise means for positively fixing the intermediate portion rigidly in contact with the receiver casing.

2. A telephone receiver casing, comprising a hollow cylindrical member having a flaring opening at one end, a separately formed reinforcing member set into said flaring opening, said reinforcing member being provided with openings into which material of the receiver and casing is molded whereby said parts are permanently locked together, said reinforcing member being provided with an internal shoulder overlying a portion of said receiver casing, said shoulder having a threaded opening and said receiver casing having a threaded opening which

forms a continuation of the opening in the reinforcing member, said threaded openings being adapted to receive a screw for supporting the receiver mechanism, and the wall of said latter opening being adapted frictionally to resist the loosening the said screw.

In testimony whereof I affix my signature in the presence of two witnesses.

LOUIS STEINBERGER.
